DESIGN FOR A COMBINED HECTOGRAPH DUPLICATING MACHINE STAND AND HEC- TOGRAPH ROLL STORAGE CABINET

John J. Flanigan, Oak Park, Ill., assignor to L. C.
Smith & Corona Typewriters, Inc., Syracuse,
N. Y., a corporation of New York

Application October 27, 1934, Serial No. 53,793

Term of patent 14 years

To all whom it may concern:

Be it known that I, John J. Flanigan, a citizen of the United States and resident of Oak Park, in the county of Cook, and State of Illinois, have invented a new, original, and ornamental Design for a Combined Hectograph Duplicating Machine Stand and Hectograph Roll Storage Cabinet, of which the following is a specification, reference being had to the accompanying drawing, forming a part hereof.

In the drawing, Fig. 1 is a perspective view of a combined hectograph duplicating machine

stand and hectograph roll storage cabinet, as seen from the front of the combined stand and cabinet, showing the new design;

Fig. 2 is a front elevation of the combined stand and cabinet; and

Fig. 3 a perspective view of the combined stand and cabinet as seen from the rear thereof.

I claim:

The ornamental design for a combined hectograph duplicating machine stand and hectograph roll storage cabinet, as shown.

JOHN J. FLANIGAN.
